Des. 957

Irah Chase Jr. of Boston Mass.
Letters Patent No 957 - Dated Oct. 20th 1857

The Schedule referred to in these Letters Patent & making part of the same.

To all whom it may concern.

Be it known, that I, Irah Chase Jr. of the City of Boston, ^{in the} County of Suffolk, and State of Massachusetts, have invented or produced a new and original design for a Grave Border or Enclosure, and I do hereby declare that the following is a full and exact description of the same.

Fig: B. represents the design in detail, with the ornamented paneled border and the Ivy Leaf edge.

2

Des. 957

Fig. A. represents the section through a. B. showing the curved line or shape of the top edge of the border.

What I claim as my invention or production is the ornaments and configurations combined as above described and shown for a grave border.
